UNITED STATES PATENT OFFICE.

JOHN F. CLEMENT, OF PHILADELPHIA, PENNSYLVANIA.

VALVELESS PNEUMATIC TOOL.

No. 928,181.

Specification of Letters Patent.

Patented July 13, 1909.

Original application filed January 24, 1905, Serial No. 242,523. Divided and this application filed October 27, 1905.
Serial No. 284,658.

To all whom it may concern:

Be it known that I, JOHN F. CLEMENT, a citizen of the United States, residing in the city and county of Philadelphia, State of Pennsylvania, have invented a new and useful Valveless Pneumatic Tool, of which the following is a specification.

My present invention, which is a division of a prior patent No. 805,633, granted to me November 28, 1905, consists of a novel construction of a valveless pneumatic tool adapted for general use in all cases where a hammer, mallet or chisel are ordinarily employed.

15 It further consists of novel features of construction, all as will be hereinafter fully set forth.

Figure 1 represents a longitudinal sectional view of a pneumatic tool embodying my invention. Fig. 2 represents a longitudinal sectional view similar to Fig. 1 but showing the hammering piston in a different relation to the parts. Fig. 3 represents a sectional view of a portion of my invention 25 showing the exhaust ports.

Similar numerals of reference indicate corresponding parts in the figures.

Referring to the drawings, 1 designates a pneumatic tool consisting of a casing 2 having a nose 3 within which is fitted the chisel bushing 4 adapted to receive the shank 5 of the chisel. A shoulder 6 on the casing 2 serves as an abutment for an outer sleeve or cylinder 7, said casing being reduced and the sleeve 7 having preferably a driving fit with the same.

8 designates an inlet piece having threaded engagement with the end of the casing 2 and provided with a shoulder 9, which latter 40 forms a tight joint between the inlet piece 8 and the end of the sleeve 7 and casing 2. The inlet piece 8 is threaded at 10 adapting the same to be readily connected with the motive fluid supply. The internal bore of 45 the casing has the different diameters 11, 12 and 13.

14 designates a piston adapted to reciprocate within the casing and consisting of the head 15 from which extends the projection 50 or head 16 and neck 17 connecting the latter with the head 18, to which is joined the neck 19, which terminates in the narrow head 20 and striker 21.

22 designates an exhaust passage open at

one end to the atmosphere and having ports 55 23 and 24 opening into the casing 2.

The operation is as follows:—The piston being in the position seen in Fig. 1, the motive fluid enters at 10, passes through the port 25, into the passage 26 and the port 27 60 being closed by the head 18, the motive fluid will pass through the port 28 around the neck 19 of the piston through the port 29, passage 30 and port 31 to the rear of the piston and acting on the enlarged head 15 will drive the 65 piston forwardly or to the left, to the position seen in Fig. 2, the motive fluid in front of the area 15 exhausting at the same time through the port 23 and passage 22 into the atmosphere. The parts being now in the 70 position seen in Fig. 2, the port 28 is closed by the head 18 and the motive fluid will pass through the port 27, around the neck 17 of the piston and acting on the head 15 will drive the piston 14 rearwardly or to the right, 75 the air in the rear of the head 15 exhausting at the same time through the port 24 and passage 22. The head 15 is always contained within the bore 11 and the different areas of the piston 16, 18 and 20 which have substantially the same diameter are adapted to move within the bore 12 while the striker 21 moves within the bore 13.

32 designates a port leading from the chamber in rear of the chisel bushing 4 to the 85 atmosphere thus preventing any cushioning of the stroke by compression of the motive fluid between the end of the striker 21 and the end of the shank 5 of the chisel.

It will be apparent that the cylinder and 90 outer casing may be made integral without departing from the spirit of my invention and that I may also if desired make slight changes in the location and arrangement of the ports and passages and in the proportion 95 of the different heads and necks of the differential piston employed and still be within the scope of my invention.

It will be seen that the motive fluid employed to drive the piston forwardly always 100 passes around the neck 19 of the piston, that the motive fluid which returns the piston always passes around the neck 17 and also that in each case the motive fluid acts on the differential areas of the piston.

I desire to call especial attention to the function of the two necks 17 and 19 whereby I differentiate the present invention from

prior devices in which only one neck is employed to control the admission of motive fluid to drive the piston both rearwardly and forwardly. In my present construction the 5 neck 19 controls the admission of motive fluid to the larger of the differential areas of the piston to drive the piston forwardly and the neck 17 controls the admission of motive fluid to the smaller differential area to drive 10 the piston rearwardly. It will be evident that by employing in this manner separate necks to control the admission of motive fluid to the different areas of the differential piston that the vibration of the tool is decreased in a large measure which makes the 15 tool not only easier to operate and less fatiguing to the operator but also much more durable.

It will be evident that various changes 20 may be made by those skilled in the art which may come within the scope of my invention and I do not therefore desire to be limited in every instance to the exact construction herein shown and described.

25 Having thus described my invention, what I claim as new and desire to secure by Letters Patent, is:—

1. In a pneumatic tool, a casing, a differential piston therein comprising an enlarged 30 head having differential areas and a striker, means on the piston near the striking end for controlling the admission of motive fluid to the greater of said areas, separate means on the piston near said enlarged head for controlling the admission of motive fluid to the smaller of said areas, and ports and 35 passages for conducting motive fluid to said areas and exhausting the same therefrom.

2. In a pneumatic tool, a casing, a differential piston therein comprising a body provided with differential areas, a plurality of 40 smaller heads, a plurality of necks connecting said heads and a striker extending from the last head, the neck nearest to said 45 striker controlling admission of motive fluid

to the rear of said piston and the neck nearest to said body controlling admission of motive fluid to the smaller area of said body.

3. In a pneumatic tool, a casing, an unapertured differential piston therein comprising an enlarged head having differential areas and a striker, means on the piston near the striking end for controlling the admission of motive fluid to the greater of said areas, separate means on the piston near 50 said enlarged head for controlling the admission of motive fluid to the smaller of said areas, and ports and passages for conducting motive fluid to said areas and exhausting the same therefrom.

4. In a pneumatic tool, a casing, a differential piston therein comprising an enlarged head having differential pressure areas, a smaller head adapted to prevent admission of motive fluid to either of said pressure 65 areas, a neck formed at the forward end of said smaller head for controlling admission of motive fluid to advance the piston, a neck formed at the rear end of said smaller head for controlling admission of motive fluid to 70 return the piston, and exhaust ports and passages controlled by said enlarged head.

5. In a pneumatic tool, an inner casing, a differential piston therein having a body provided with differential areas and having a 75 plurality of smaller heads, a plurality of necks connected with said heads and a striker, the neck farthest from said body controlling admission of motive fluid to the rear of said piston, the neck nearest to said body 80 controlling admission of motive fluid to the smaller area of said body, an outer casing secured on said inner casing, an inlet piece having threaded engagement with said inner casing and a flange on said inlet piece en- 85 gaging said casings.
